UNITED STATES PATENT OFFICE.

JOHN J. MURPHY, OF TOLEDO, OHIO, ASSIGNOR, BY MESNE ASSIGNMENTS, TO THE AMERICAN CORTÉ-SCOPE COMPANY, OF TOLEDO, OHIO.

STEREOSCOPE.

1,101,948.

Specification of Letters Patent.

Patented June 30, 1914.

Application filed November 18, 1912. Serial No. 731,915.

To all whom it may concern:

Be it known that I, JOHN J. MURPHY, a citizen of the United States, residing at Toledo, Lucas county, Ohio, have invented 5 a new and useful Stereoscope, of which the following is a specification.

This invention relates to features of a support and the adjustable extension therefor.

This invention has utility when embodied 10 as a support and position or range finder if used in connection with stereoscopes.

Referring to the drawing: Figure 1 is a fragmentary perspective view of an embodiment of the invention in connection with a stereoscope; Fig. 2 is a side elevation of the device as embodied in Fig. 1; Fig. 3 is a side elevation of the device collapsed; and Fig. 15 4 is a section on the line IV—IV, Fig. 3, looking in the direction of the arrow.

20 The stereoscope is shown as provided with the hood 1 having a pair of lenses 2 and centrally between the lenses and projecting therefrom a pair of inclined partitions 3 mounted upon the hood or lens carrying frame. Between the partition or divider members 3 is disposed the socket 4 for mounting the hood, lens and divider section of the stereoscope upon the supporting stem 5 which has the extended seat 6 and ledges 25 7 for rigidly positioning the support relatively to the stereoscope. Extending upward through the support and flanging outward are the claws 8 between which and abutting the support are the projections 9 30 of the member 10 having the pivot bearing 11 for mounting the foldable handle 12 which has in one side thereof the slot 13. The support has a pair of sides 14 upwardly and inwardly inclined to form a channel 35 10 in the bottom of which is the slot 15 for the member 16 extending therebelow.

Rigid with the member 16 is the adjustable partition or divider 17 having the pair 45 of flare wings 18 at the forward end thereof. This adjustable partition or divider of the range finder has the pivoted arm 19 foldable thereagainst. This arm 19 has a view abutting portion readily adapting the device for use as a position and range finder 0 or focusing bar, the member 19 being disposed to abut the line of division between the stereoscope views 20, which views may be incorporated in a book 21 in connection 5 with descriptive matter as desired. The member 16 of the reciprocable section of

the range finder is provided with finger engaging portions 22 in such proximity to the handle 12 that the operator or reader may support the stereoscope by the handle 12 and simultaneously reciprocate the range finder 60 17, 19 to the desired focus, while the other hand is free to hold the book or turn pages therein. The spring 24 coacting between the bottom of the members 14 and the top of the member bearing the finger engaging portions 22 introduces such frictional resistance to reciprocation of the secondary or adjustable divider 17 that it readily stays in any adjusted range.

This device has special application in increasing the range of usefulness of stereoscopes in that views for third dimensional showing may be readily incorporated in catalogues as well as matters of current literature and with a device of this disclosure 70 at hand there is a convenient and ready means for enlightening the reader as to devices as fully as though seen in the three dimension condition. The manipulation is readily accomplished by one hand not only 75 as to positioning the scope but as to finding the range. Furthermore there is introduced a positive guard against interference by cross view between the separate showings of the illustration by means of the adjustable divider or partition 17. This may be desirably spaced a short distance back from the views so as not to shade either view. This auxiliary divider contributes considerable ease to the use of this device to supplement 80 general reading, for in the course of the reading the stereoscope may be taken up, manipulated with one hand, and the view readily fixed with no chance for interference. Further, the device is of such form as to compactly collapse and pack away for handling 85 in connection with the particular books, should such packing be desired.

The stereoscope support and finder herein 90 is not only adapted for use in connection with regular stereoscopic view cards, but for observing any stereoscopic views, whether in a roll, in a book, say specially designed, or views scattered anywhere through general volumes, price lists, or with reading matter, 95 as no special construction is necessary.

What is claimed and it is desired to secure by Letters Patent is:

1. A one hand stereoscope holder and focus 100 finder embodying the combination with a 110

stereoscope having lenses, a hood, a grip portion for hand engagement rigid with the lenses and hood, a reciprocable focus finder movable relatively to the lenses and hood, and an actuating connection for the finder extending in proximity to the grip portion and independent thereof for simultaneous engagement and actuation.

2. A stereoscopic focus finder embodying a supporting section having a handle, stereoscopic lenses and a hood rigid with the sup-

porting section, and an adjustable section provided with operating means extending along the supporting section and independent of the handle.

In testimony whereof I affix my signature in the presence of two witnesses.

JOHN J. MURPHY.
